(57) CLAIM

The ornamental design for a waterpail cork holder, as shown and described.

DESCRIPTION

FIG. 1 is a right side, front and top perspective view of a waterpail cork holder showing my new design;

FIG. 2 is a left side, bottom and back perspective view thereof;

FIG. 3 is a front view thereof; and,

FIG. 4 is a back view thereof.

The broken lines depict portions of the waterpail cork holder that form no part of the claimed design.
